O. A. NEWMAN

VIOLIN BOW

Original Filed Oct. 12, 1922

— INVENTOR

Otto A. Newman.

BY
Geo. P. Kimmel.
ATTORNEY.

UNITED STATES PATENT OFFICE.

OTTO A. NEWMAN, OF EDWARDSPORT, INDIANA.

VIOLIN BOW.

Application filed October 12, 1922, Serial No. 594,051. Renewed May 29, 1925.

To all whom it may concern:

Be it known that I, OTTO A. NEWMAN, a citizen of the United States, residing at Edwardsport, in the county of Knox and State 5 of Indiana, have invented certain new and useful Improvements in Violin Bows, of which the following is a specification.

This invention relates to violin bows, more particularly to the tip and frog thereof, and 10 has for its object to provide, in a manner as hereinafter set forth, a violin bow formed with a tip and a frog, each having means for securely fastening the bow hair in position as well as permitting of the disconnection 15 thereof, from the tip or frog or from both, when desired.

Further objects of the invention are to provide a violin bow having means for connecting and disconnecting the hair thereto, 20 and which is simple in its construction and arrangement, strong, compact, efficient and convenient in use, readily set up in cooperative relation with respect to the staff of the bow and inexpensive to manufacture.

With the foregoing and other objects in view, the invention consists of the novel construction, combination and arrangement 30 of parts, as hereinafter more specifically described and illustrated in the accompanying drawings, wherein is shown an embodiment of the invention, but it is to be understood that changes, variations and modifications can be resorted to which come within the 35 scope of the claims hereunto appended.

In the drawings wherein like reference characters denote corresponding parts throughout the several views:—

Figure 1 is a sectional elevation of the frog end of the violin bow, showing the 40 adaptation therewith of a frog, in accordance with this invention.

Figure 1^a is a grouped perspective of the frog.

Figure 2 is an end view thereof,

Figure 3 is a section on line 3—3, Figure 1,

Figure 3^a is a section on line 3^a—3^a, Figure 1,

Figure 4 is a longitudinal sectional view 50 of a tip, in accordance with this invention,

Figure 5 is a rear view of the tip,

Figure 6 is a section on line 6—6, Figure 4,

Figure 7 is a longitudinal sectional view 55 of a modified form of tip,

Figure 8 is a cross sectional view thereof 55 looking toward the rear end of the tip,

Figure 9 is an inverted plan of the form of tip shown in Figure 7.

Referring to the drawings in detail, 1 denotes the polygonal shaped rear end of the 60 staff of the bow and which is provided with a longitudinally extending bore 2; the latter is intersected by a vertically disposed pocket 3, which opens at the lower side of the staff. Rotatably mounted in the bore 2, is an adjusting bar 4, which is threaded intermediate 65 its ends as at 5. Attached to the rear end of the bar 4, as well as abutting against the rear end of the staff, is a nut 6, which is employed for conveniently rotating the 70 bar 4.

Referring to Figures 1, 2 and 3 of the drawings which illustrate a frog in accordance with this invention, 7 denotes the body portion of the frog, which may be formed 75 of any suitable material, preferably aluminum and which has its end provided with a transverse groove 8, and with a vertically disposed pocket 9. The pocket 9, is of inverted V-shape and with the walls thereof each formed with an outwardly extending 80 notch 10. The bottom of the body portion 7, is formed with a longitudinally extending groove 11, having each of the walls thereof oppositely beveled and conforming in contour to the notch 10, as at 12. The forward portion 13, is of less depth than the rear portion thereof and terminates in a chamfered portion 14, which is upwardly inclined. The body portion 7, has a forward extension 15, with the sides and top thereof chamfered as at 16, thereby providing a shoulder 17. Mounted on the extension 15, is a metallic cap 18, which conforms in contour to the 85 contour of the extension 15, the latter being 90 semi-oval in cross section. The bottom of the cap 18, is spaced from the chamfered portion 14, of the extension 15.

The body portion 7, is positioned against the lower side of the hexagonal end 1, of 100 the body portion and is formed with a series of spaced vertically disposed sockets 19, 20, 21 and each of which has its wall threaded. Carried by the bar 4, is a threaded collar 22, having an integral peripherally threaded 105 arm 23, depending therefrom, and which engages with the threaded wall of a socket for coupling the frog to the staff. The frog

is adjusted in a longitudinal direction with respect to the staff by rotating the bar 4, thereby causing the collar 22, to shift thereon, and such action will move the frog either 5 forwardly or rearwardly depending in what direction the bar 4, is rotated. The series of sockets provide means for adjustably connecting the frog to be longitudinally shifted the distance desired, or in other words, the 10 sockets enable the frog to be connected to the staff at different distances with respect to the rear terminus thereof, for example, if the arm 23, engaged in the socket 21, the frog would be positioned at a greater distance 15 forwardly with respect to the rear terminus of the staff then if the arm 23, engaged in the socket 20, or 19, and this provides for different adjustment of the frog for the purpose of tightening the bow hair 20 24.

The body portion 7, is formed with a pocket 25, which opens into the forward part of that portion of the groove 11, of greater depth and said pocket is adapted to 25 receive the terminus 26, of the bow hair 24, and the latter, when connected to the frog, is arranged below the extension 15, extends through the portion 13 of the groove 11, and is then projected up into the pocket 30 25, as shown in Figure 1.

The bow hair 24, is detachably secured to the frog by a wedge 27, a holding member 28, and a clamping member 29. The wedge 27, is interposed between the extension 15, 35 and the bottom of the cap 18. The holding member 28, is mounted in the portion 13, of the groove 11, and the clamping member 29, is mounted in the pocket 8, the pocket 9 and in that portion of the groove 11, of 40 greater depth and abuts against the upturned terminus of the bow hair 24, and further abuts against the rear end of the holding member 28 for clamping it in position against said cap 18.

45 The clamping member 29 is angle-shaped and embodies a vertically disposed arm and a horizontally disposed arm. The side edges of the horizontal arm conform in shape to the side walls of the lower part of the pocket 50 9 and further conform in shape to the side walls of the groove 11. The vertical arm of the member 29 conforms in shape to the shape of the pocket 9 and groove 8, and is formed with an opening through which extends a bolt 30, and with the latter having threaded engagement with the threaded walls of the socket 31, which is formed in the rear end of the body portion 7. When the clamping member is secured to the body 60 portion 7, the horizontal arm is flush with the bottom of the body portion 7, and the vertical arm is flush with the rear end of the body portion 7.

65 Referring to Figures 4, 5 and 6 of the drawings, which illustrate one form of bow

tip, the latter is formed with a hollow shank 32, adapted to receive the forward end of the staff of the bow, and said shank terminates at its forward end in a depending head 33, formed at its rear with a transverse 70 groove 34, and also provided with a pocket 35, which opens at the bottom thereof. Each of the side walls of the pocket 35, is oppositely beveled, as at 36, and the said pocket 35, is closed by an angle shaped clamping member 37, which is seated in the groove 34, and has its side edges conform to the contour of the side walls of the pocket. The bow hair 24, is extended up into the pocket 35, and is secured against the forward wall 38, of the pocket 35, by the clamping member 37, the latter is detachably secured in position, by a bolt 39, which extends through one of the legs of the clamping member 37, and has threaded engagement with the threaded 80 walls of the socket 40, formed in the head 33. The bow hair 24, is extended around the bottom of the clamping member 37, and said bottom forms what may be termed a bearing 90 for the forward terminal portion of the bow hair 24.

Referring to Figures 7, 8 and 9 of the drawings, which illustrate a modified form of bow tip, the latter includes a hollow shank 41, in which is adapted to be mounted the forward end of the staff of the bow and depending from the forward terminus of the shank 41, is a head 42, provided with a pocket 43, into which opens a socket 44, having the wall thereof threaded. The forward terminal of the bow hair 24, is secured to the head 42, by a detachable clamping member 44, which is semi-oval in cross section, and around which the forward terminal of the bow hair 24, is positioned. The clamping member 44, is detachably secured to the head 42, by a bolt 45, which has threaded engagement with the walls of the socket 44. The outer face of the clamping member 44, which is flat, provides a bearing for the forward terminal portion of the bow hair 24. The clamping member 44, is mounted in the pocket 43, and the bow hair is secured between said member and the walls of the pocket 43, as shown in Figure 7 of the 110 drawings.

The clamping element 29, the clamping member 37, and the clamping member 44, each is countersunk for the reception of the headed end of the bolt employed for detachably securing it in position.

From the foregoing description taken in connection with the accompanying drawings, a violin tip and frog are set up whereby the terminals of the bow hair are securely held in position and furthermore the construction of the tip or of the frog is such that when required, a terminal of the bow hair can be conveniently disconnected, and although the drawings illustrate the pre- 125 130

ferred embodiment of the invention, yet it is to be understood that changes in the details of construction can be resorted to without departing from the spirit of the invention.

What I claim is:—

1. A violin bow frog comprising a body portion formed intermediate its ends with a pocket for the reception of one end of the bow hair and in its bottom with a groove communicating intermediate its ends with said pocket for the reception of the bow hair, said body portion further provided with an extension, a cap mounted on the extension and depending therefrom and providing a passage for the bow hair, a wedge positioned against the bottom of the extension for clamping the bow hair against said cap, a holding member seated in said groove and abutting against said cap for retaining the bow hair in said groove, an angle-shaped clamping member seated in said groove and in the rear end of the body portion and having its inner end engaging said holding member for clamping it in position and further having its inner end clamping the end terminal portion of the bow hair within said pocket and means for detachably securing said clamping member to said body portion.
2. A violin bow frog comprising a body portion formed with a series of vertically disposed spaces threaded sockets, adjustable means carried by the staff of the bow and engaging in any one of said sockets for adjustably connecting the body portion to the staff, said body portion provided at its bottom with a groove and further provided intermediate its ends with a vertically disposed pocket for the reception of the rear terminal portion of the bow hair, said pocket opening into said groove, a cap mounted on said body portion for connecting the bow hair therewith, a wedge extending into said cap for clamping the bow hair thereto, a holding member seated in said groove and positioned against said cap for maintaining the bow hair in said groove, and a clamping element seated in said groove and in the rear end of said body portion and detachably connected with the body portion and having its inner end engaging one end of said holding member for clamping it in position and further engaging the bow hair for securing it in said pocket.

3. A violin bow frog comprising a body portion formed with a series of vertically disposed spaced threaded sockets, adjustable means carried by the staff of the bow and engaging in any one of said sockets for adjustably connecting the body portion to the staff, said body portion provided at its bottom with a groove and further provided intermediate its ends with a vertically disposed pocket for the reception of the rear terminal portion of the bow hair, a cap mounted on said body portion for connecting the bow hair therewith, a wedge extending into said cap for clamping the bow hair thereto, a holding member seated in said groove and positioned against said cap for maintaining the bow hair in said groove, and a clamping element detachably seated in said groove and in the rear end of the body portion and engaging one end of said holding member for clamping it in position and further engaging the bow hair for securing it in said pocket, one of said sockets terminating in the upper end of said pocket and the other of said sockets arranged forwardly and rearwardly in the body portion with respect to said pocket.

4. A violin bow frog comprising a body portion formed with a series of vertically disposed spaced threaded sockets, adjustable means carried by the staff of the bow and engaging in any one of said sockets for adjustably connecting the body portion to the staff, said body portion provided at its bottom with a groove and further provided intermediate its ends with a vertically disposed pocket for communicating with said groove for the reception of the rear terminal portion of the bow hair, a cap mounted on said body portion for connecting the bow hair therewith, a wedge extending into said cap for clamping the bow hair thereto, a holding member positioned in said groove for maintaining the bow hair therein, and a clamping element detachably seated in said groove and in the rear end of the body portion and having one end thereof clamping said holding member in the groove and the bow hair in said pocket, and said body portion and said clamping element having associated means to provide a dove-tail connection therebetween.

In testimony whereof, I affix my signature hereto.

OTTO A. NEWMAN.
